CLAIM

The ornamental design for a combined toy sand box and lid, as shown and described.

DESCRIPTION

FIG. 1 is a perspective view of a combined toy sand box and lid showing my new design;

FIG. 2 is a perspective view thereof with the lid removed;

FIG. 3 is a front elevational view thereof;

FIG. 4 is a top plan view thereof;

FIG. 5 is a side elevational view thereof with the lid in a raised position, all sides being substantially identical; and

FIG. 6 is a top plan view thereof with the lid removed.

FIG. 1

FIG. 2

FIG. 3

FIG. 4

FIG. 5

FIG. 6
